UNITED STATES PATENT OFFICE.

HENRY RIEF, OF GRAND RAPIDS, MICHIGAN, ASSIGNOR TO NATIONAL SPRING & WIRE COMPANY, OF GRAND RAPIDS, MICHIGAN, A CORPORATION OF MICHIGAN.

SPRING-HANDLING IMPLEMENT.

Application filed June 5, 1924, Serial No. 718,166. Renewed June 1, 1926.

This invention relates to tools and more particularly to a tool or implement for handling a plurality of coiled springs.

Many articles of manufacture such as mattresses, furniture cushions, automobile seats and the like contain resilient elements such as coiled wire springs. These springs are enclosed or partially enclosed in pockets in a bag or covering structure of canvas or other fabric. This fabric is first stitched to form pockets and the springs thereafter inserted in the pockets.

The object of my invention is to produce a tool or implement adapted to hold a plurality of springs in compressed form so that, when inserted within the structure, the springs may be released and permitted to enter the pockets simultaneously, thus greatly facilitating the manufacture of the article in which such springs are used.

This object and the various advantages of the invention will appear as the implement is better understood, the invention consisting substantially in the novel construction, combination and arrangement of parts illustrated in the accompanying drawings and hereinafter described and pointed out in the appended claims.

In the drawings:—

Fig. 1 is a top plan view of a tool or implement embodying my invention, showing a plurality of springs held therein.

Fig. 2 is a side elevation of the same, showing the springs held in compressed position.

Fig. 3 is a side elevation of the lower bar member of the implement, showing the springs expanded when the upper bar member has been removed.

Fig. 4 is a sectional view, enlarged, of one end of the implement, the section being in the vertical plane indicated by the dotted line 4—4 of Fig. 1.

Fig. 5 is a sectional view, also enlarged, of the locking device at the handle end of the implement, the section being in the vertical plane indicated by the dotted line 5—5 of Fig. 1.

My novel implement comprises two main bar members indicated as a whole by the letters A and B, each long and each relatively thin and narrow. The lower member A is a long, relatively narrow metal bar 1, to which is rigidly secured at one end a handle C. The lower surface of the bar 1 may

be provided with a central, longitudinally extending strengthening rib 2. The forward end of the bar 1 is bifurcated to form a recess 3 suitably shaped to accommodate a movable clamp member D.

The clamp member D is mounted upon the free end of a resilient member E, preferably made of flat spring metal, by rivets 4 or other suitable means. The latch member, at its free end, extends upwardly through the recess 3, which end is provided with a latch 5 which extends inwardly, i. e. toward the handle, a slight distance. The under face of the latch 5 is of such shape as to overlie and engage the top surface of the end of the top member B, as clearly indicated at 6 in Fig. 3.

The spring or resilient member E is secured to the under surface of the lower bar 1 by rivets 7 or other suitable means.

The upper bar member B is a straight, relatively narrow metal bar, not so long as the bar 1. It is bent or offset at one end, as indicated at 8, and is provided at this offset end with a recess 9, adapted, when the bars A and B are together, to register with the recess 3 in the bar A. The clamp member D is thus adapted to enter this recess 9 so that the latch 5 will engage the top surface of the member B at 6 as before stated. The top member B may also be provided with a longitudinally extending strengthening rib 10, if desired. The rear or handle end of said top member B is bifurcated to form a recess 11 for the reception of a locking member F.

The member F is pivotally mounted through an opening 12 in the lower member A, to a retaining nut 13 suitably secured on the under surface of the bar 1, and it carries a handle or finger hold 14 and a locking or latch shoulder 15, which latter is adapted to engage the top surface of the top member B adjacent to the recess 11. An expansion spring 16, mounted over studs 17 and 18 on the members F and A respectively, exerts tension to normally press the member F away from the handle C and to hold its shoulder 15 in engagement with the top member B, as shown in Fig. 5.

When the members A and B are in proper position, a plurality of springs G may be compressed between their proximate surfaces as clearly shown in Figs. 1, 2 and 4. In this position, the implement is ready for

its intended use, and may be inserted in a mattress or other article which is to contain the springs G, and the member F then moved against the spring 16 to the position indicated in dotted lines in Fig. 5. The shoulder 15 thus being free from contact with the top surface of the top member B, the latter may be raised upwardly and moved longitudinally, so that its other end will slip from under the latch 5. The member B may then be withdrawn from the mattress or other article. When the bar B is withdrawn from the mattress, the springs G will at once expand as shown in Fig. 3 and be free to position themselves in place in the mattress. The withdrawal of the bar B from the mattress is easy because it has no shoulders or protuberances to contact with the ends of the springs G or with the fabric of the mattress. The withdrawal of the lower bar A is similarly easy because the top surface of the latch 5 is suitably rounded and the spring E causes said latch 5 to move down upon the flat surface of the bar as shown in Fig. 3.

This tool or implement is cheap to manufacture, easy to manipulate, effective and accurate in use and has no complicated parts to work loose or get out of order. It may be made available for other uses than those hereinabove referred to. Its effectiveness does not depend upon the precise form or structure herein rather fully described and therefore my invention is not limited to such details, except as the same may be stated in the claims herein made.

I claim as my invention:—

1. An implement for inserting a plurality of springs in a confined space, comprising two bar members each relatively narrow and thin, adapted in superposed relation to hold a plurality of coiled springs between them, and means at their respective ends for removably locking said two bars together.

2. A spring holding implement comprising two superposed bars, means for holding together the adjacent ends of said bars, comprising a member yieldingly attached to one bar, extending around its end, and adapted to engage the end of the other bar.

3. A spring holding implement comprising two superposed bars, means for holding together the adjacent ends of said bars, comprising registering recesses in the end of each bar, a clamp member adapted to engage said recesses, a latch on the end of said clamp member adapted to engage one of said bars adjacent to its recess and means for yieldingly attaching said clamp member to the other bar.

4. A spring holding implement comprising two superposed bars, means for holding together the adjacent ends of said bars,

comprising registering recesses in the end 65 of each bar, a clamp member adapted to engage said recesses, a latch on the end of said clamp member adapted to engage one of said bars adjacent to its recess and means for yieldingly attaching said clamp member to the other bar, said attaching means including a flat spring member secured at one end to the clamp member and at its other end to the bar.

5. A bar provided at one end with a 75 clamp member and at its other end with a locking member, a second bar provided with recesses in each end adapted to be engaged by the said clamp and the said locking member of the other bar, and means for 80 yieldingly holding the locking member in engaged position with the second bar.

6. A bar provided at one end with a clamp member and at its other end with a locking member, a second bar provided with recesses in each end adapted to be engaged by the said clamp and the said locking member of the other bar, and means for 85 yieldingly holding the locking member in engaged position with the second bar, said 90 holding means embracing an expansion spring.

7. A bar provided with a movable clamp member yieldingly secured to its under side and adapted to extend about one of its 95 ends, and a locking member pivotally mounted at its other end, in combination with a second bar provided with a recess in each end and to be engaged by said clamp and locking members of the first mentioned 100 bar, and means for normally compressing the pivoted locking member in a direction toward the clamping member.

8. An implement of the class described comprising a bar member provided at one 105 end with a handle and at its other end with a recess, a second bar straight throughout the major portion of its length and at one end provided with an offset and a recessed end, a clamp member yieldingly secured to 110 the bottom of the first mentioned bar and extending about the ends of the two bars when in superposed relation, a latch on the free end of the clamp member adapted to engage the top of the second bar, a latch member pivotally secured to the handle end of the first mentioned bar, adapted to engage the recessed end of the second bar, a locking shoulder on said pivoted locking member and means uniting the locking member and the first mentioned bar and adapted to press said locking member outwardly in locking position.

In testimony, that I, claim the foregoing as my invention I affix my signature, this 125 2nd day of June, 1924.

HENRY RIEF.
